[57] CLAIM

The ornamental design for a storage and display stand
for hole cutting saws, as shown and described.

DESCRIPTION

FIG. 1 is a top-plan view of a storage and display stand
for hole cutting saws, showing my new design;

FIG. 2 is a front-elevational view thereof;

FIG. 3 is a bottom-plan view thereof;

FIG. 4 is a cross-sectional view taken substantially
along line 4—4 of FIG. 2;

FIG. 5 is a side-elevational view thereof; and

FIG. 6 is a rear-elevational view thereof.

FIG. 1

FIG. 4

FIG. 2

FIG. 5

FIG. 3

FIG. 6
